3
Table 1

Example No.	Compound	Boiling point (°C./mm.)
3	N-phenyl-N'-n-butylformamidine	104-106/0.1
4	N-phenyl-N'-n-octylformamidine	128-138/0.1
5	N-phenyl-N'-n-decylformamidine	158-163/0.03
6	N-phenyl-N'-n-dodecylformamidine	170-174/0.075
7	N-phenyl-N',N'-di-n-propyl formamidine	108-114/0.35
8	N-phenyl-N',N'-di-n-butyl formamidine	115-120/0.25
9	N-phenyl-N',N'-di-iso-butyl formamidine	100-102/0.1
10	N-phenyl-N',N'-di-n-amyl formamidine	130-138/0.25

EXAMPLES 11-42

A further large number of N-phenyl formamidines substituted in the phenyl radical are set out below in Table 2 as Examples 11-42. These substances were prepared by processes analogous to that described in Example 1, but using the appropriate substituted O-ethylisoformanilide instead of O-ethylisoformanilide, and using the appropriate aliphatic amine instead of n-hexylamine.

Table 2

Example No.	Compound	Boiling point (°C./mm.)
11	N-o-chlorophenyl-N'-n-hexylformamidine	140-148/0.25
12	N-o-chlorophenyl-N'-n-octylformamidine	164-170/ .25
13	N-m-chlorophenyl-N'-n-hexylformamidine	137-143/ .25
14	N-m-chlorophenyl-N'-n-octylformamidine	162-170/ .5
15	N-p-chlorophenyl-N'-n-hexylformamidine	136-144/ .1
16	N-p-chlorophenyl-N'-n-octylformamidine	162-164/ .25
17	N-3,4-dichlorophenyl-N'-n-hexylformamidine	168-174/ .4
18	N-3,4-dichlorophenyl-N'-n-octylformamidine	168-174/ .15
19	N-2,4-dichlorophenyl-N'-n-butylformamidine	132-136/ .05
20	N-2,4-dichlorophenyl-N'-n-octylformamidine	168-174/ .05
21	N-2,4,5-trichlorophenyl N'-n-butylformamidine	144-148/ .025
22	N-2,4,5-trichlorophenyl N'-n-octylformamidine	164/ .005
23	N-o-tolyl-N'-n-butyl formamidine	105-110/ .25
24	N-o-tolyl-N'-n-hexylformamidine	128-136/ .05
25	N-o-tolyl-N'-n-octylformamidine	172-175/ .1
26	N-m-tolyl-N'-n-hexylformamidine	130-140/ .1
27	N-p-tolyl-N'-n-hexylformamidine	146-152/ .1
28	N-p-tolyl-N'-n-octylformamidine	174-178/ .1
29	N-2,6-dimethylphenyl-N'-n-butylformamidine	110-120/ .01
30	N-2,6-dimethylphenyl-N'-n-hexylformamidine	147/154/ .8
31	N-2,6-dimethylphenyl-N'-n-octylformamidine	154-158/0.25
32	N-2,4-dimethylphenyl-N'-n-butylformamidine	114-121/0.1
33	N-2,4-dimethylphenyl-N'-n-hexylformamidine	128-140/ .075
34	N-2,3-dimethylphenyl-N'-n-butylformamidine	114-123/ .05
35	N-2,3-dimethylphenyl-N'-n-hexylformamidine	143-147/ .05
36	N-2,5-dimethylphenyl-N'-n-butylformamidine	116-124/ .18
37	N-2,5-dimethylphenyl-N'-n-hexylformamidine	140-145/ .02
38	N-3,4-dimethylphenyl-N'-n-butylformamidine	130-134/0.25
39	N-3,4-dimethylphenyl-N'-n-hexylformamidine	120-133/0.1
40	N-p-ethoxyphenyl-N'-n-hexylformamidine	164-170/0.5
41	N-p-dimethylaminophenyl-N'-n-butylformamidine	90/ .005
42	N-p-dimethylaminophenyl-N'-n-octylformamidine	140/ .005

EXAMPLE 43

This example describes the preparation of N-phenyl-N'-dodecylacetamidine.

A mixture of O-ethylisoacetanilide (8.2 parts) and n-dodecylamine (6.8 parts) dissolved in toluene (25 parts) was heated under reflux for 2 hours. The toluene was then removed by distillation under reduced pressure leav-

ing a residue from which was distilled N-phenyl-N'-dodecylacetamidine, B.P. 150-160° C./0.001 mm.

EXAMPLES 44 AND 45

5 Two other N-phenyl acetamidines (shown in Table 3 below as Examples 44 and 45) were prepared by the process of Example 43, but using n-hexylamine and n-octylamine respectively instead of n-dodecylamine.

Table 3

Example No.	Compound	Boiling point (°C./mm.)
15	N-phenyl-N'-n-hexylacetamidine	114-120/ .05
44	N-phenyl-N'-n-octylacetamidine	130-138/ .005

20

EXAMPLE 46

This example describes the preparation of N-2-pyridyl-N'-n-butylformamidine.

25 A mixture of 2 - ethoxymethyleneiminopyridine (7 parts) and n-butylamine (4 parts) was dissolved in toluene (25 parts) and the resulting solution heated under reflux for 2 hours. The toluene was then removed by distillation under reduced pressure and the residue distilled to give N-2-pyridyl-N'-butylformamidine, B.P. 176-180° C./18 mm.

EXAMPLES 47-49

30 Three further N-2-pyridylformamidines, shown in Table 4 below as Examples 47-49) were prepared by the process of Example 46 but using the appropriate aliphatic amine instead of the butyl amine of that example.

Table 4

Example No.	Compound	Boiling point (°C./mm.)
47	N-2-pyridyl-N'-n-hexylformamidine	124-130/0.1
48	N-2-pyridyl-N'-n-octylformamidine	168-172/0.1
49	N-2-pyridyl-N'-n-dodecylformamidine	178-182/0.001

50 The herbicidal properties of a large number of amidines of this invention are illustrated by the screening tests described below in which the compounds have been tested as herbicides by being sprayed in the form of liquid compositions on the following plant species: wheat (*Triticum spp.*), wild oats (*Avena spp.*), mustard (*Brassica alba*), kale (*Brassica oleracea*), sugar beet (*Beta vulgaris*), red clover (*Trifolium pratense*) and cleavers (*Galium aparine*).

55 The herbicidal compositions tested were liquid compositions containing 0.05 lb. of amidine as active ingredient per gallon of water and the compositions were applied to the test plants at the rate of 100 gallons/acre, i.e. the active ingredient was applied at the rate of 5 lb./acre. The compositions contained also 0.3% by weight of a wetting agent consisting of a 27% aqueous solution of the condensation product of one mole of octyl cresol with 7-8 moles of ethylene oxide. Where the amidine used was water-soluble, the liquid composition was made simply by dissolving the amidine and the wetting agent in water; but amidines not sufficiently soluble in water were first dissolved in a small quantity of methanol and the resulting solution mixed with sufficient water to provide a liquid composition containing 0.05 lb. of amidine/gallon of water.

60 The results obtained are set out in Table 5 below in which the herbicidal activity of each of the compounds tested has a grading number from 0 to 4. These grading

numbers relate to the effect of the test compounds on the plants sprayed and have the following meanings:

- 0 ----- Complete kill.
- 1 ----- Very severe damage with partial kill.
- 2 ----- Severe damage.
- 3 ----- Moderate damage.
- 4 ----- Slight damage.

phenyl and pyridyl; R₂ is selected from the group consisting of hydrogen and methyl; R₃ is alkyl of from 4 to 12 carbon atoms; and R₄ is selected from the group consisting of hydrogen and alkyl, provided that where R₄ is alkyl, the sum of carbon atoms of R₄ and R₃ taken together is not greater than 16, and the herbicidally effective acid addition salts of said compounds.

Table 5

Compound of Example No.	Wheat	Wild Oats	Mustard	Kale	Sugar Beet	Red Clover	Cleavers
3	3	3	1	1	3	4	3
1	3	3	0	1	0	1	1
6	3	3	0	0	0	2	3

47	3	4	2	1	2	3	2
49	2	2	1	3	1	3	1

*Compound applied at the rate of 2-lb./acre.

What I claim is:

A method for the destruction and control of vegetation, in which the vegetation is treated with a herbicidal amount of a compound selected from the group consisting of compounds having the formula:

wherein R₁ is selected from the group consisting of phenyl, chlorophenyl, lower alkyl phenyl, lower alkoxy

phenyl and pyridyl; R₂ is selected from the group consisting of hydrogen and methyl; R₃ is alkyl of from 4 to 12 carbon atoms; and R₄ is selected from the group consisting of hydrogen and alkyl, provided that where R₄ is alkyl, the sum of carbon atoms of R₄ and R₃ taken together is not greater than 16, and the herbicidally effective acid addition salts of said compounds.
